SAMUEL A. FITE, OF PHILADELPHIA, PENNSYLVANIA, ASSIGNOR
TO HIMSELF AND JOHN H. MANSUR, OF SAME PLACE.

Letters Patent No. 92,522, dated July 13, 1869.

IMPROVEMENT IN NECKTIE-RETAINERS.

The Schedule referred to in these Letters Patent and making part of the same.

To all whom it may concern:

Be it known that I, SAMUEL A. FITE, of the city of Philadelphia, in the county of Philadelphia, and State of Pennsylvania, have invented a new and improved Necktie or Collar-Holder; and I do hereby declare that the following is a full, clear, and exact description thereof, which will enable others skilled in the art to make and use the same, reference being had to the accompanying drawing, forming part of this specification.

The object of this invention is to provide a simple, efficient, and ornamental holder and fastener for the necktie or collar.

It consists in the peculiar construction of parts arranged for attachment to the stud or shirt-button, and adapted to impart a vertical pressure to the collar, under the folds, for stiffening it; also, to press the collar or necktie snugly to the neck, and to prevent the collar or tie from disconnection with the stud, as herein-after more fully specified.

The drawing represents an elevation of a shirt-front and collar, with my improved device attached.

Similar letters of reference indicate corresponding parts.

A represents a spring wire, shaped to fit the curvature of the neck for a short distance each way from the centre of the front, having two return bends B C, extending downward and backward, terminating a short distance each side of the position of shirt-stud D, in hoods E, forming seats for other abrupt bends of the said wire, from which the two ends F spring up in

nearly semicircular curves toward the centre of the throat, and down to the stud D, where they are provided with curved recesses for embracing the neck of the stud behind the head.

From each of the hoods E, and connecting them, another spring G rises, in a regular curve, above the parts F of the wire A.

The whole device rests on the stud D, and provides an upward tension under the folds of the collar, calculated to keep it in position and prevent it from doubling over.

It also presses the band of the collar around the neck, and may be made equally serviceable in supporting a bow or necktie.

It may be instantly put on or taken off.

It is also ornamental, and may, if preferred, be covered with silk or other tissue, arranged in ornamental form.

Having thus described my invention,

What I claim as new, and desire to secure by Letters Patent, is—

The necktie or collar-holder, constructed as described, of the curved wire A B C, the curved spring-wires F F, and the curved spring G, both ends of G and the outer ends of F being connected to the spring parts C of the wire A, by means of the hoods E, all arranged as described, for the purpose specified.

SAMUEL A. FITE.
